UNITED STATES PATENT OFFICE.

JOHN M. YOUNG, OF NEW YORK, N. Y., ASSIGNOR TO AMERICAN CAN COMPANY, OF NEW YORK, N. Y., A CORPORATION OF NEW JERSEY.

KEY-OPENING CAN.

Application filed December 29, 1921. Serial No. 525,600.

To all whom it may concern:

Be it known that I, JOHN M. YOUNG, a citizen of the United States, residing in New York, in the county of New York and 5 State of New York, have invented a new and useful Improvement in Key-Opening Cans, of which the following is a specification.

My invention relates in general to containers and more particularly to key-opening 10 cans provided with a side tearing strip extending circumferentially about the body and having a tongue extending from the body at its side seam for engagement by a key to remove the tearing strip.

15 Key opening cans of this character ordinarily have the top secured thereto in a double seam, and it is desirable to have a tearing strip and the tongue, which is engaged for removal of such strip, near said 20 double seam, or in other words, near the top of the container. The side seam by which such containers are ordinarily closed is of the lock and lap type, in which the body or wall edges are hooked together. When a 25 tearing strip tongue is provided at this seam, it is the practice to leave unhooked that portion of the seam from which the tongue extends and difficulty has been experienced in securing the body edges above the tongue 30 together in the lock seam in such manner that they will hold during the usual soldering operation upon the side seam, this difficulty resulting from the short distance between the tongue and the top of the 35 container.

It is a principal object of my invention to provide means for joining the body edges in the vicinity of the tearing strip and the tongue extending therefrom in such manner 40 that they will be firmly held together during the soldering operation and will not interfere with the proper formation of the tongue.

45 A further object of the invention is the provision of a container of this character in which the lock seam is dispensed with about and above the tearing strip tongue without detrimentally affecting the joint in that area, and in which a different and suitable union of the parts is provided without appreciable expense or difficulty.

55 Numerous other objects and advantages of the invention will be apparent as it is better understood from the following description, which, taken in connection with

the accompanying drawings, discloses a preferred embodiment thereof.

Referring to the drawings,

Figure 1 is a side elevation of a container in which my invention is embodied, a part 60 thereof being shown in section and the top being omitted for convenience of illustration;

Fig. 2 is an enlarged horizontal section taken substantially on the line 2—2 in Fig. 65 1; and

Fig. 3 is a similar section taken substantially on the line 3—3 in Fig. 1.

For the purpose of illustrating my invention I have shown upon the drawings a container body 11 having a bottom end 12 suitably secured thereto and being provided with an upper flange 13 adapted to be folded in a double seam with a cover or end flange 70 in the well known manner. Near the top 75 of the body and immediately beneath the double seam, when the can is closed, is a tearing strip area 14 set off by score lines 15 and 16 and having extending therefrom on the outside of the body wall a tearing 80 strip tongue 17 adapted to be engaged by a key or otherwise for removal of the tearing strip to open the can. The body wall is formed with a side seam 18 which throughout the greater part of its length is of the 85 lock and lap form illustrated in Fig. 2, in which the body wall edges 19 and 21 are respectively locked in a hook formed in the opposite edge. It has been found necessary 90 to omit this locked or hooked joint at the point 22 at which the tongue 17 takes off 95 from the seam, and since there is but a short space between said tongue and the top of the container when the tearing strip is positioned near the double seam in the desirable manner, there is not a sufficient length of lock and lap seam at this point to hold the body edges together during the usual process of applying solder to the exterior of 100 the seam.

My invention obviates this difficulty by providing merely a lap seam from a point 23 beneath the lower score line 16 to the top 105 of the body wall, thus permitting the tongue 17 to extend straight out from the line of the seam, and by securing the edges 24 and 25 together by spot welding at the points 26 and 27 on opposite sides of the tearing strip. In this manner a firm union is provided at the top of the body wall above the 110

score lines as well as below without in any way interfering with the proper formation of the tongue 17.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

15 1. A can, comprising a body scored circumferentially near its top to provide a side tearing strip adapted to be removed to open the can, said body being provided with a lock and lap side seam and having a 20 tongue extending from the tearing strip at said seam, and the part of the seam above a point located beneath the lower score line being lapped but not locked and being welded above and below the strip set off by 25 said score lines.

2. A can, comprising a body scored circumferentially near its top to provide a side tearing strip adapted to be removed to open the can, said body being provided 30 throughout the greater part of its length with a lock and lap side seam, and the metal edges from a point beneath said score lines to the top of the body being lapped merely and welded outside the score lines.

3. A can, comprising a body scored circumferentially near its top to provide a side tearing strip adapted to be removed to open the can, said body being provided with an interfolded side seam throughout the greater part of its length and having a tearing strip tongue extending from one of its side edges in line with said seam and the metal edges above said interfolded seam being overlapped and welded on opposite sides of the tearing strip. 35

4. A sheet metal container having a seam and a tearing strip extending across said seam and set off by score lines from the body of the container at each side of the tearing strip, and having a tongue, the body of the 50 container having at each side of the tearing strip an integral welded connection between the outer sheet metal layer of the body and the contiguous underlying layer forming a part of said seam. 55

5. A key-opening can, comprising a body and a top secured thereto in a double seam, said body being circumferentially scored near said double seam to provide a line of severance for removal of the top, and having a tongue extending from the side thereof at said score lines, said body being provided with a lap side seam in its upper part, from which said tongue extends, and said seam being spot welded at each side of the 60 tongue to provide a firm union of the edges about the point of departure of the tongue. 65

JOHN M. YOUNG.
